UNITED STATES PATENT OFFICE.

THOMAS A. COLEMAN, OF VREDENBURGH, ALABAMA, ASSIGNOR TO PETER VREDENBURGH, JR., OF VREDENBURGH, ALABAMA.

FEED-ROLLER CONSTRUCTION.

1,241,925.

Specification of Letters Patent.

Patented Oct. 2, 1917.

Application filed October 28, 1915. Serial No. 58,414.

To all whom it may concern:

Be it known that I, THOMAS A. COLEMAN, a citizen of the United States, residing at the town of Vredenburgh, county of Monroe, and State of Alabama, have invented a certain new and useful Improvement in Feed-Roller Construction, of which the following is a full, clear, and exact description, such as will enable others skilled in the art 10 to which it appertains to make and use the same, reference being had to the accompanying drawings, forming part of this specification.

This invention relates to certain new and 15 useful improvements in feeding rollers for lumber machines, said rollers being of that general type wherein the work engaging members which are carried on the roller are removably secured in position so that they 20 may be replaced when worn.

The specific improvement constituting the subject matter of the present invention resides in a novel fashion of seating and securing the engaging elements and in certain 25 novel constructions of the various parts incident thereto.

Experience has shown in the use of these devices that in the handling of heavy and hard lumber the teeth of engaging elements 30 carried by the roll for the purpose of securing a working engagement with the lumber become quickly worn down to a greater or less extent, thereby impairing the efficiency of the device.

35 In the present improvement, I provide a construction wherein the seating of the engaging elements is such that they may be reversed when they have become worn in part, as a consequence of which reversal new 40 working points are presented in proper disposal to engage the lumber.

A further object is to provide an improved form of mounting for the work engaging elements by virtue of which they 45 are brought against the work in such manner that the thrust is delivered against their mountings and not against them in such fashion as would tend to bend or distort them.

50 A further object of the invention is to provide an improved construction of parts whereby the detachable engaging elements may be reversed in the roller and disposed

in such relationship as to avoid their distortion by work thrusts and stresses. 55

The invention relates, furthermore, to the provision of improved forms of engaging elements for use in rollers of a general character.

Other and further objects will be obvious 60 or hereinafter pointed out.

In the accompanying drawings—

Figure 1 represents a longitudinal view partly in section and partly in elevation of a feeding roller embodying certain features 65 of my invention.

Fig. 2 represents a transverse section substantially on line 2—2 of Fig. 1 and illustrating the fashion in which the engaging elements coöperate with material. 70

Fig. 3 is a detail showing in perspective one end of one of the beveled bars or engaging elements adapted for use in this roller.

Fig. 4 is a detail showing a cross section through one end of one of the toothed bars, 75 the same being taken approximately on line 4—4 of Fig. 3.

Fig. 5 is a detail illustrating in perspective a portion of an improved form of engaging element or toothed bar. 80

Fig. 5^a is a vertical section through the same.

Fig. 6 is a detail illustrating a portion of another modified form of toothed bar.

Fig. 6^a is a vertical section through the 85 same.

Fig. 7 is a partial cross section of a roller carrying the modified forms of bars.

By reference to the illustrations, it will be understood that 1 represents a shaft 90 which is suitably journaled and driven. Screw-seated on this shaft are terminal clamping collars 2, intermediate which are disposed carriers 4 in the form of cylindrical drums which are freely mounted on the 95 shaft for both longitudinal and circumferential movement thereon. These drums have their corners beveled back from their faces, and are provided with longitudinal slots or seats 5 extending from end to end. 100 As is best seen in Fig. 2, these slots or seats are disposed non-radially in the carriers,

i. e. tangential to a circle concentric with the drum's axis, said slots extending inwardly on a line which would subtend an 105 arc considerably less than half the circum-

ference of the carrier. In these non-radial slots are disposed toothed bars or engaging elements 6, in the form of thin steel bars which are a trifle longer than the carriers and which have sloping extremities, and marginal teeth formed on one edge thereof. As best seen in Figs. 2 and 3, the cross sectional form of these toothed bars is such that the teeth therein have two corners or 10 points, one in the plane of each side face of the bar.

Intermediate the movable carriers 4 are movable clamping collars 7 having their opposite faces undercut so as to extend over 15 the beveled ends of the carriers and the sloping extremities of the engaging elements. These clamping collars, like the carriers, are freely movable both longitudinally and circumferentially on the shaft, so 20 that pressure may be transmitted through them from engaging elements on one carrier to engaging elements on the others. The terminal clamping collars 2 are undercut on one side in a fashion similar to the 25 clamping collars 7 so as to engage the outer ends of the terminal carriers and the engaging elements thereon. One of the clamping collars 2 is designed to form a fixed abutment, and hence may be fixed to the shaft, 30 but one of said collars must be movable longitudinally on the shaft, as by virtue of its screw thread mounting, so that it may be moved into and out of engagement with the adjacent carrier and engaging elements.

35 With the carriers and clamping collars disposed on the shaft as described, and the engaging elements disposed in the grooves or seats of the carriers, the movable terminal collar 2 may be moved toward the other 40 terminal collar, forcing the juxtaposed engaging elements, carriers and clamping collars into engagement *seriatim* longitudinally of the shaft, whereby the overhanging peripheral portions of the clamping collars 45 are caused to engage over the ends of the engaging elements and force and clamp them securely into the seats, due to the sloping or inclined form of their contacting parts. When in their proper relative positions, the 50 terminal clamping collars, operating by the pressure or compression exerted through the engaging elements and interspaced clamping collars, serve to hold the carriers and clamping collars securely on the shaft for 55 rotation therewith, and the engaging elements firmly and securely seated in the carriers.

With the engaging elements thus seated in the carriers, as is seen in Fig. 2, the tooth 60 points along one side of a bar or engaging element will be farther from the shaft than the tooth points along the other side of a bar. This, of course, is due to the non-radial position of the bars in the carriers. In 65 operation, the roller is rotated in the direc-

tion of pitch of the engaging elements, which is the direction indicated by the arrow in Fig. 2. As the lumber represented by L, Fig. 2, is fed to the roller, it is engaged by the outer series of tooth points of the engaging elements, which afford a purchase on the lumber whereby the movement necessary to feed it forward to the saws may be transmitted from the revolving roller. It will be seen that in this operation, the thrust and reaction exerted against the engaging elements are exerted in the line of the engaging elements and not across them as it is in instances where they are disposed radially in the carriers. This brings the thrust 70 through the maximum width of the material in the engaging elements and against the bottoms of the seats in which they are secured. By virtue of this arrangement, the possibility of distorting or bending the 75 toothed bars is greatly decreased.

As it will be seen how in this operation the points or corners along only one side of a bar will be brought into operative engagement with the lumber, it is obvious that wear 80 on an engaging element will be confined to one side of the bar. When the engaging elements become so worn on one side as to lose their efficiency, they may be reversed in their seats by loosening up the movable 85 terminal clamping collar, moving the carriers until the engaging elements are disengaged from the clamping collars, then extracting the engaging elements from their 90 seats and reversing them end for end. By 95 this operation, the sides or corners of the bars which before were at the underside or nearer the periphery of the carriers, will be at the outer side or on the greater radius, and hence will be the corners or edges which 100 will engage the lumber. Not having been 105 subject to wear when the opposite edges or corners were the active ones, the edges or corners now active will be sharp and give the 110 rollers the proper efficiency. In this fashion 115 by simple reversal of engaging elements or toothed bars, the roller may be provided with a new and sharp work surface, without entailing loss of time or expense in sharpening or replacing the work engaging portions. 120

It is obvious that with the engaging elements disposed in this non-radial position, their sloping ends will extend some distance circumferentially across the undercut faces of the clamping collars. In order to increase 125 the contact surface between the ends of the engaging elements and the clamping collars, the sloping ends of the former are given a slightly rounded contour, as shown in Fig. 3, such contour being that which will follow 130 the face of the clamping collar. Furthermore, as shown in Fig. 3, each end will be beveled in opposite directions at the proper angle so as to give increased contact surface. The ends are beveled in opposite directions 135

from a medial line so as to provide contact surfaces for both positions of the engaging elements, that is, for its original position in the carrier, and for its reversed position 5 above described.

In Figs. 5, 5^a, 6 and 6^a, I have shown two other forms of toothed bars. These are designed for use where a very sharp working surface is required, and it will be observed 10 that instead of being simply serrated, the toothed edge is beveled in a third direction, forming pyramidal teeth having a flat front face and a sharp point. Toothed bars of this form are designed for use in rollers wherein 15 the engaging elements are disposed in either radial or non-radial position. With this form of toothed bar a most effective feeding engagement with the lumber is obtained, with the least amount of scoring or marking 20 on it by the bars. The flat front faces on the teeth prevent their breaking through the material, while the sharp points pierce through the fiber without splintering it and the rearwardly beveled portion clears the 25 surface of the lumber so as to leave no mark. In the form illustrated in Figs. 5 and 5^a the rear bevel is straight, whereas in the form illustrated in Figs. 6 and 6^a the rear bevel is curved.

30 In Fig. 7 is shown a partial cross section of a roller in which bars of the form illustrated in Figs. 5 to 6^a inclusive are disposed in non-radial position. It will be observed that in such construction the working points 35 project forwardly so as to have a somewhat hooklike action as they meet the lumber. This insures their taking a better grip on the lumber, and is of particular importance in operating upon heavy timbers and when 40 the speed of the feeding roller is high.

For use with soft lumber, it may not be desirable, and is not necessary, to form the engaging elements with the serrations or teeth, and in such instances, with my im- 45 proved roller construction, simply a plain bar of rectangular cross section may be used efficiently. Due to the non-radial setting of the bar, it is not necessary to bevel its operating side down to an edge in order 50 to secure proper working engagement, as the slanting position of the bar in the carrier presents its rectangular corner to the work in proper relationship to secure the effective working engagement necessary to feed the 55 lumber. In this plain form of bar, when one corner is worn down, the other corner may be brought into operative position by simply reversing the bar as described above.

From the foregoing, it will be observed that 60 my improved construction provides a feeding roller wherein the engaging elements are removably disposed in such position as to best withstand the stresses to which they are subjected, and in which they are most efficient 65 in securing an effective feeding operation.

It will be observed, furthermore, that by virtue of this construction, the work engaging elements may be to all effects renewed by simply reversing them in their seats so as to present new working portions. It is 70 thus obvious that my improved construction provides a feeding roller which is both very efficient in operation and very economical in upkeep.

I am aware that the devices herein illustrated and described are susceptible of further changes and modifications without departing from the spirit and scope of the invention indicated in the following claims.

What I claim is:

1. A feeding roller including a substantially cylindrical carrier, said carrier being provided with longitudinal slots extending thereinto tangentially relative to a circle concentric therewith, longitudinally extending 85 bars seated in said slots and having projecting portions extending outwardly beyond the carrier and pitched in the direction of rotation thereof, said projecting portions being formed with beveled rear faces and 90 with flat front work engaging faces adapted to engage material to feed it with rotary movement of the carrier, and means for securing the bars in the slots.

2. A feeding roller including a revolvably 95 mounted carrier, said carrier being provided with longitudinal slots about its periphery extending into the carrier tangentially relative to a circle concentric with its axis, engaging elements in the form of bars removably mounted in said slots and having portions projecting from the carrier and beveled to form hook-like members pitched in the direction of rotation of the roller and adapted to engage lumber to feed it with 100 rotary movement of the carrier, and means coöperating with the extremities of the engaging elements to clamp them into the slots.

3. In a feeding roller, a substantially cylindrical carrier mounted for rotative movement, engaging elements in the form of bars extending longitudinally of said carrier and removably mounted therein so that they extend outwardly from the periphery of the carrier and are pitched in the direction of 110 the latter's rotation, whereby their engagement with material when in operation tends to force them into their seats, the projecting portions of said engaging elements about the periphery of the carrier being formed with 115 flat front faces to engage lumber to feed it upon rotative movement of the carrier.

4. A feed roller comprising the combination of a substantially cylindrical carrier, engaging elements removably seated in said carrier in positions tangential to a circle concentric with the carrier, said engaging elements having work engaging edges at opposite sides thereof adapted to engage lumber to feed it upon rotary movement of 125 130

the carrier, and removable means coöperating with said engaging elements whereby to secure them in the carrier.

5. In a feed roller, the combination of a substantially cylindrical carrier, a longitudinally extending bar seated therein and extending from the periphery thereof tangentially relative to a circle concentric with the carrier, said bar having work engaging edges at the opposite sides thereof and being reversible in the carrier so as to dispose either of said edges in operative position, and means coöperating with the extremities of said bar for clamping it in the carrier.
- 15 6. In a feed roller, the combination of a substantially cylindrical carrier, a clamping collar longitudinally movable relative thereto, and an engaging element in the form of a longitudinally extending bar seated in the carrier and having its extremity extending beyond the end of the carrier and curved for engagement with the clamping collar, by which engagement the engaging element is clamped in its seat.
- 25 7. In a feed roller, the combination of a cylindrical carrier, a clamping collar having a reëntrant clamping face, and an engaging element seated in the carrier tangentially relative to a circle concentric therewith and having its extremity extending beyond the end of the carrier and beveled transversely

to afford surface contact with the clamping face of the collar.

8. In a feeding roller, the combination of a substantially cylindrical carrier, engaging elements seated therein and extending from the periphery thereof pitched in the direction of rotation of the roller, said engaging elements having flat forward faces and their rearward sides beveled in the direction in which said engaging elements are pitched, the arrangement providing peripherally disposed hook-like members for engaging lumber to carry it forward upon rotation of the roller.

45 9. In a feeding roller, a work engaging element comprising a flat bar having its operating edge formed by a longitudinal series of serrations and a lateral bevel extending from the apices of the serrations at the rearward side of the bar to provide sharp work engaging points along the margin of the bar and flat work feeding faces at the forward side thereof.

50 In testimony whereof I hereunto affix my signature in the presence of two witnesses, this 21st day of October, 1915.

THOMAS A. COLEMAN.
